UNITED STATES PATENT OFFICE.

FRANKIE M. COLSON, OF SALT LAKE CITY, UTAH.

SUPPORTER.

1,225,581.

Specification of Letters Patent.

Patented May 8, 1917.

Application filed May 12, 1916. Serial No. 97,128.

To all whom it may concern:

Be it known that I, FRANKIE M. COLSON, a citizen of the United States, residing at Salt Lake City, in the county of Salt Lake 5 and State of Utah, have invented new and useful Improvements in Supporters, of which the following is a specification.

The invention relates to garment supporters, and comprehends a structure which may 10 be independently used as a supporter, or may be connected to the corset, for use as a pendent supporter therefrom.

The improved structure includes a supporting member adapted to encircle the 15 waist or to be secured to the corset, to which member are secured elastic pendent straps, the lower ends of the straps adjustably supporting a garter.

The invention in the preferred form of 20 details will be described in the following specification, reference being had particularly to the accompanying drawings, in which:—

Figure 1 is a view showing the supporter 25 developed;

Fig. 2 is a side view showing the same applied to a corset.

The improved garment supporter includes a belt section 1, constructed of webbing or 30 the like, primarily adapted to encircle the waist of the user, the terminals of the belt sections being provided with fastening means 2 and 3, whereby they may be connected to secure them together.

Pendent from the belt section at appropriate points on each side portion thereof, are straps 4, the upper ends of the straps being secured by stitching or the like to the belt section, and the lower ends pass 40 through horizontal loop portions 5 of connectors 6, the return lengths of the straps 4 being connected to the main lengths by adjustable buckle connectors 7. The connectors 6 for two of the straps 4 are metallic pieces formed to present a horizontal section having the loop 5 and a vertical section having parallel elongated openings 8. One of the connectors 6, that used for the end strap, is formed with the horizontal loop or eye 5, but in place of the duplicate parallel openings 8 of the other connectors, 50 is formed with a single opening 9 of greater width than either of the openings 8.

Mounted in the connectors 6 is a garter section 10, of appropriate length, one terminal being secured through the loop openings 9, by stitching, while the opposing terminal is passed through an engaging member 11 and the terminals connected beyond the engaging member for adjustment by buckle 60 connectors 12. The intermediate portion of the garter section is passed through the connectors 5, being extended reversely through the respective loop openings 8 of each of said connectors, as shown in Fig. 1 of the 65 drawings.

In use, the waist section is secured about the waist of the user, so that the straps 4 are pendent on one side, front and rear of the legs. The straps 4 are of sufficient 70 length to permit the garter sections to be passed about the legs, immediately below the knee, the adjustment of the various parts being such as to permit the necessary holding action, while yet avoiding undue 75 restriction or freedom of movement.

If desired, the belt section may be secured directly to the corset 13, as shown in Fig. 2, the remaining parts of the device and their use being identical with that described. 80 Furthermore, the waist section or garter section may be constructed of elastic webbing or other material, as for example, an ordinary leather strap like section may be substituted for either. It is of course to be 85 understood that the engaging member 11 is provided with a lip 14 to engage in the elongated openings 9 of the terminal connector 6 when the garter section encircles the legs. The various connectors are here 90 shown as stamped from metal, although it is to be understood, that they may be constructed in any desired manner, and of any desired material without departing from the spirit of the present invention. 95

Having described my invention, what I desire to secure by Letters Patent is:—

A garment supporter including a waist section in the form of a strap, means for adjustably connecting the terminals of the 100 strap, a plurality of garter sections, connector straps intermediate the garter sections and waist section, metal connectors carried by the connector straps and supporting the garter sections to permit independent 105 longitudinal adjustment of the

garter sections with respect to the connected straps, an engaging member carried by one free end of each of the garter sections, one of said metal connectors being formed with an opening to receive one terminal of the garter section and of sufficient size to permit the coupling therewith of the engaging

member carried by the opposite end of the garter section.

In testimony whereof I affix my signature. *to*
FRANKIE M. COLSON.

Attest by witnesses:

SAMUEL W. STEWART,
CATHERINE ODESSA SHAW.
